PUSH-PULL AMPLIFIER FOR RELAXATION OSCILLATIONS

Herbert Bähring, Berlin-Zehlendorf, Germany,
assignor to the firm of Fernseh Aktiengesellschaft, Zehlendorf, near Berlin, GermanyApplication April 1, 1937, Serial No. 134,411
In Germany April 2, 1936

5 Claims. (Cl. 250—27)

This invention relates to arrangements for simultaneous amplification of relaxation oscillations and exciting impulses as are used, for instance, in electrical television transmitting and receiving systems for analyzing or synthesizing images.

The impulses available to control the relaxation oscillations, for instance, frame or line synchronizing impulses, do mostly not have the theoretically desired shape, for instance, exact rectangular shape, but are more or less distorted. They may consist, for instance, of a series of short impulses which rise above an irregular interference oscillation. Furthermore, they must be amplified to an amount which makes a secure control of the relaxation circuit possible. If a tube of the oscillating circuit was simultaneously used for impulse amplification, these interferences would also be amplified and be noticeable on the image. On the other hand, it is not desirable to provide for an extra amplifier stage for the exciting impulses because the cost of the entire set will thereby be increased.

Therefore, it is the object of this invention to apply the exciting impulses in the same phase to two amplifier paths in push-pull, whereas the relaxation oscillation voltage is applied in opposite phase to these amplifier paths so that compensation of the exciting impulses and their interferences occurs in a load resistance.

This arrangement has the advantage that the same tube may simultaneously be used for amplification of the relaxation oscillation and for amplification of the pulses without allowing interferences in the impulses or the impulses proper to influence the amplified relaxation oscillation. The amplifier tube, which represents one of the two amplifier paths, may be used at the same time as blocking tube in a two-tube reflex relaxation circuit.

It is a further advantage that impulses of opposite phase may be obtained between anode and cathode of both push-pull tubes if the load is inductive. These impulses are produced by the saw-tooth shaped voltage at the grid and by the voltage produced by the saw-tooth shaped current according to the law

$$L \frac{di}{dt}$$

These impulses may be used as positive or negative impulses for the synchronization of further circuits.

The drawing shows embodiments of the invention.

Fig. 1 shows a diagram of the push-pull circuit independent of the relaxation oscillation circuit to be used. Fig. 2 shows an embodiment in which one of the two push-pull tubes is used as a blocking tube of a two-tube relaxation circuit. Fig. 3 shows a further embodiment in which the grid voltage of opposite phase for a second tube is taken from a resistor in the screen grid lead of the amplifier tube.

The tubes 1 and 2 in Fig. 1, in this case are screen grid tubes, to the input 3, 4, 5, of which the relaxation oscillations are applied in opposite phase, and to the input 6 and 7, of which the exciting impulses are applied in the same phase. The plate circuits of the tubes are connected by a load resistor 8 in such a manner that the amplified relaxation oscillation may be taken from 9 and 11 and the amplified exciting impulses may be taken from 9 and 10, and 10 and 11, respectively. The resistor 8 is center-tapped. When using magnetic deflection, the resistor is substituted by a choke. A resistor 12 is provided in order to compensate for non-uniformity of the tubes. A resistor 13 and a condenser 14 serve to produce the bias for the tubes, and a resistor 16 makes the adjustment of the screen grid voltage possible. The condenser 17 serves as a coupling condenser for the synchronizing impulses.

If both tubes are exactly alike, compensation of the exciting impulses applied at 6 and 7 occurs also if resistance 12 is not provided. As the screen grid currents are of opposite phase, the resulting current variation in the resistor 12, and thereby the variation in screen grid voltage caused by the screen grid relaxation current in 12, is nil. Thus, there is no reaction of the screen grid on the control voltage so that a pure saw-tooth wave will be amplified. In this case, the short-circuiting condenser 15 may also be eliminated whereby the input impedance of the impulse circuit will be increased. If, however, the tube 1 has an amplification factor of μ_1 and a plate resistance R_{11} , and the tube 2 has an amplification factor of μ_2 and a plate resistance R_{22} , the value R_2 of the resistance 12 for interference compensation will be divided by a tap 18 in a part r_1 on the side of tube 1, and a part r_2 on the side of the tube 2 in such a manner that

$$\frac{r_2}{r_1+r_2} = \frac{\mu_1(R_{12} + \frac{Ra}{2})}{\mu_2(R_{21} + \frac{Ra}{2})}$$

wherein Ra is the impedance of the resistor 8.

50 55

In Fig. 2 the push-pull circuit is joined with a two-tube reflex relaxation circuit. The push-pull circuit corresponds to that of Fig. 1 except that the synchronizing impulses are not applied to the screen grids of the push-pull tubes, but to the control grids in the same phase, by means of a resistor 27. The grid of a discharge tube 22 is connected by a condenser 23 with the plate circuit of the tube 1. The tube 22 serves the periodical discharge of the condensers 29, 31, 35 and 36. The charging current is taken from a supply source at the points 19 and 20, and flows through the devices 21 and 26 which may, for instance, be resistors or saturated diodes which allow the flow of a substantially constant current. The condensers 29 and 31, and 35 and 36, respectively, form a capacitive voltage divider, the taps of which are connected with the grids of the tubes 1 and 2. The resistances 24 and 25 serve to adjust the discharge period of the condenser 23. The operation of this circuit is as follows: The relaxation period is started by applying a negative impulse to the grids of the two push-pull tubes 1 and 2 at the points 6 and 7. This causes an increase in plate potential by the same amount in both tubes 1 and 2 so that the deflecting system connected at 9 and 11 remains uninfluenced. The change in plate potential in the tube 1, in respect to its cathode, which change is greater than the impulse on the grid, is applied to the grid of the discharge tube 22 by means of a coupling condenser 23. The discharge tube 22 begins to draw plate current. The amplitude of the impulses on the grid of the discharge tube must lie approximately 1 to 2 volts above the noise level, which is caused by variations of the voltage supply, for instance, the rectifier arrangement or by electrostatic or magnetic interference. The charging of the condensers 29, 31, 35 and 36 over 21 and 26 is disturbed in such a manner that the plate current of the tube 1 is still further decreased, and the impulse applied to the grid of the tube 22 becomes still more positive. The condensers 29, 31, 35 and 36 discharge through the tube 22 and through the resistors 32 and 33. The voltage drop caused by the discharge current in the resistors 32 and 33 aids the back feed. The tube 22 is not blocked and remains in this condition through the period of back feed over the resistors 32 and 33, respectively, i. e., during the discharge of the condensers 29 and 31, and 35 and 36, respectively, or during the length of the synchronizing impulse if this is shorter than the discharge period. During the discharge period the grid of the tube 22 becomes so strongly positive that it draws grid current. During the discharge these electrons flow through the condenser 23. After the discharge is completed they cause a negative charge the grid of the tube 22, so that this grid becomes completely blocked. The charge of the condenser 23 will equalize itself through the resistance 24, the condenser 23, the condenser 17 and one-half of the resistor 8, according to their time constants. The resulting voltage on the grid is thus not only dependent on the character of the exterior resistance, but also upon the time constants of these elements. Furthermore, they can be shifted by a constant amount by varying the potentiometer 25. During the rise of the curve its instantaneous value, however, is of such a magnitude that it prevents the tube 22 from drawing plate current. Because of the blocking of the discharge tube, the charg-

ing of the condensers 29, 31, 35 and 36 occurs through the devices 21 and 26. The charging occurs in opposite phase symmetrically to the cathode of the tubes 1 and 2, which are grounded through the bias device 13 and 14. A voltage rising in opposite phase is applied to the grids of the push-pull tubes at the voltage dividing taps during the charging period of the condensers. The screen grid currents and plate currents of the tubes 1 and 2 also vary in opposite phase so that the voltage variation on the screen grids is nil, while the variation in plate current will be made useful by utilization of saw-tooth current in the resistance 8, or by taking a saw-tooth voltage from the resistance 8. If both halves of the load resistance 8 are dynamically coupled, it is possible to swing both amplifier tubes in the non-linear range of the characteristic in order to obtain a resulting saw-tooth curve.

If the synchronizing impulse comes to its end after the condenser has started to charge, the anode potentials of both tubes 1 and 2 will become more negative by the same amount, so that no interference in the image will be noticeable. The increased negative bias on the grid of the blocked tube 22 has only the effect of blocking this tube still more. The length of duration of the synchronizing impulse is, therefore, of no importance for the circuit.

Fig. 3 shows a circuit in which the tubes 1 and 2 are not arranged symmetrically, but in which the grid voltage of opposite phase for the tube 2 is taken from a resistance in the screen grid lead of the tube 1. In order to obtain the same amplitude of voltage on the grid of tube 2, as on the grid of tube 1, and to cause the same potential variations in the plate circuits of both amplifier tubes by the synchronizing impulses applied to the grid, the resistors 43 and 41 must have such values that they fulfill the following equations:

$$R'_{2'} = \frac{1}{\mu} R_{i2}$$

$$R_1 = R'_{2'} \left(\frac{\mu_1}{\mu_2} - 1 \right)$$

The above relationship represented in the first equation is derived from a consideration of the two tubes operating in the push-pull amplification of the relaxation oscillations. Such oscillations are applied to the grid of tube 1, across the resistors 30 and 32, and are derived from the relaxation oscillator circuit associated with the tube 22. The derivation of the formula is as follows. The relaxation oscillation voltage applied to the grid of tube 1 is amplified a total of μ_2 times where μ_2 is the amplification factor of the tube taken between the control grid and screen grids. It follows, that the voltage applied to the control grid of the tube 2 must equal the screen grid voltage of tube 1 divided by the amplification factor μ , in order to realize the same plate voltages in the plate circuits of both tubes. The total effective voltage of screen grid circuit of tube 1 is divided across a circuit of R_1 , $R'_{2'}$ and R_{i2} in series, of which $R'_{2'}$ is the resultant of resistors 41 and 43 in parallel and constitutes the portion from which the signal is obtained and applied to the control grid of the tube 2. Hence

$$\frac{R'_{2'}}{R_1 + R'_{2'} + R_{i2}} = \frac{1}{\mu_2}$$

from which

$$R'_{2'} = \frac{R_{i2}}{\mu_2}$$

The second formula is derived from a consider-

ation of the two tubes 1 and 2 operating as amplifiers for the synchronizing impulses applied to the screen grid of the tube 1. Since both tubes are presumed to be identical, the amplification factor μ_1 of tube 2 taken between the control grid and plate will be the same as the amplification factor of tube 1. However, the synchronizing impulses are not applied to the control grid of tube 1, but to the screen grid of tube 1, and consequently the amplification factor of tube 1 with respect to signals applied to the screen grid, will be different and equal to μ_3 . Of the signals applied to the screen grid of tube 1, a portion thereof will be applied to the control grid of tube 2, this portion being equal to the ratio of the equivalent resistance 41+43 over the sum of this equivalent resistance + the resistance 40 which may be expressed as

$$20 \quad \frac{R'_2}{R'_2 + R_1}$$

where R'_2 = the equivalent resistance of 41+43 in parallel and R_1 = resistance 40. To obtain the same effect in the plate circuits of both tubes, the 25 values of R'_2 and R_1 must be such that

$$R'_2 \times \mu_1 = (R'_2 + R_1) \mu_3$$

Simplifying this equation to obtain a value for R_1 , one obtains

$$30 \quad R_1 = R'_2 \left(\frac{\mu_1}{\mu_3} - 1 \right)$$

The condenser 42 is a coupling condenser; the condensers 45 and 46 serve as by-pass. The operation of the relaxation device formed by the tubes 35 1 and 22 is exactly the same as that of the tubes 1 and 22 and the circuit according to Fig. 2. The circuit does not require a supplementary plate supply source for generation of the saw-tooth voltage of opposite phase.

40 I claim:

1. In combination, a source of relaxation oscillations, a source of control impulses, and common means for simultaneously amplifying said relaxation oscillations and said control impulses and applying said amplified control impulses to said source of relaxation oscillations to control the frequency thereof.

2. In combination, a source of relaxation oscillations, a source of control impulses, a pair of electron discharge devices, means including said discharge devices for amplifying said control

impulses to obtain a balanced output therefrom, means also including said discharge devices for amplifying said relaxation oscillations to obtain an unbalanced output therefrom, and means connecting one half of said balanced output to 5 said source of relaxation oscillations to control the same.

3. In combination, a source of relaxation oscillations, a source of control impulses, a pair of electron discharge devices, means including said discharge devices for amplifying said control impulses in push-pull relationship to obtain a balanced output therefrom, means also including said discharge devices for amplifying said relaxation oscillations in push-pull relationship to obtain an unbalanced output therefrom, and means connecting one half of said balanced output to 10 said source of relaxation oscillations to control the frequency of the same.

4. In combination, a pair of electron discharge 20 devices connected in push-pull, a condenser charging circuit apportioned equally between the input circuits of said electron discharge devices, a separate electron discharge device connected across said input circuits, and having a control 25 grid, means for applying impulses to said input circuits in phase to provide amplified impulses in balanced output in the output circuits of said push-pull connected discharge devices, and means for connecting the control grid of said 30 separate device to the output circuit of only one of said push-pull connected devices.

5. In combination, a pair of electron discharge 35 devices having output circuits connected in push-pull arrangement, a condenser charging circuit, means for applying potentials from said charging circuit out of phase to the input circuits of said electron discharge devices to provide amplified potentials across the push-pull connected output 40 circuits, a separate electron discharge device connected across said condenser charging circuit, and having a control grid, means for applying synchronizing impulses in phase to said input circuits of said pair of electron discharge devices to provide amplified impulses in balanced output 45 in the push-pull output circuits of said discharge devices, and means for connecting the control grid of said separate device to only one of said push-pull connected output circuits.
